UNITED STATES PATENT OFFICE.

MARLIN CRONER, OF LONGTON, KANSAS.

MECHANIC'S ADJUSTABLE TRESTLE.

No. 926,320.

Specification of Letters Patent. Patented June 29, 1909.

Application filed May 5, 1908. Serial No. 431,064.

To all whom it may concern:

Be it known that I, MARLIN CRONER, a citizen of the United States, residing at Longton, in the county of Elk and State of Kansas, have invented certain new and useful Improvements in Mechanics' Adjustable Trestles, of which the following is a specification, reference being had therein to the accompanying drawing:

10 My invention relates to trestles for the use of carpenters, joiners, plasterers, painters, and other mechanics: and the object of the invention is to provide a trestle which can be constructed at a small cost, is light in weight, 15 and can be easily and quickly adjusted at different elevations, thereby rendering unnecessary a large number of trestles of various heights for the numerous uses for which they are required in building and other mechanical employments.

Another object of this invention is the provision of means for expeditiously disconnecting the component parts of the trestle for reasons which will hereinafter appear obvious.

To the accomplishment of the recited objects and others coördinate therewith, the preferred embodiment of my invention resides in that construction and arrangement 30 of parts hereinafter described, illustrated in the accompanying drawings, and embraced within the scope of the appended claims.

In said drawings: Figure 1 is a perspective view of the trestle embodying this invention. 35 Fig. 2 is a vertical section of one of the uprights and a portion of the cross-beam, the extension being indicated by dotted lines. Fig. 3 is a central vertical section of the metallic casing and the trestle legs, and Fig. 4 is 40 a side elevation of one of the uprights and a portion of the cross beam, showing the graduations on the upright.

Similar reference numerals indicate corresponding parts throughout the several views.

45 As contemplated by my invention, the cross beam 1, having a suitable metallic protective covering 2 on opposite sides thereof, is adapted to be detachably connected to the uprights 3, provided with a similar covering 50 4, by means of right-angular sockets 5, which I temporarily secure by fastening means, such for example, as bolts 6. The sockets 5 are terminally connected by the diagonally disposed braces 7, and in this manner, rigid-

ity is imparted to the cross beam 1. It will 55 also be noted that the inner side portion of each socket extends upward vertically and lies contiguous the inner side of the horizontal portion of the socket thus serving as a stop for the terminals of the cross beam. I 60 prefer to graduate the uprights 3 at intervals of six inches along the vertical extent thereof, as exhibited at 8, in Fig. 4 of the drawings, and in conjunction with the foregoing organization of cross beam, uprights, and 65 connections therefor, I have devised means for adjusting the assemblage, or the trestle proper, vertically, said means comprising a casing 9, of substantially triangular contour in cross section, cast or formed of a single 70 piece of metal, and having a central socket 10 for the reception of said uprights 3, which when elevated to the desired position, may be engaged by the screws 11, and thus secured. This structure is adapted to be supported by legs 12, which are fastened to the 75 outside inclined sides of the metallic casing 9, preferably by bolts 13.

As will appear obvious, I can attain any elevation of the trestle that convenience may 80 dictate, by simply manipulating the screws 11, and incident the adjustment, very little strength need be exerted, owing particularly to the lightness of the cross beam and uprights, and the slight frictional resistance. 85 The metallic covering on opposite sides of the uprights not only insures a free movement of the uprights with respect to the socket, but off-sets the pressure of the screws on the wooden portion of the uprights. The corresponding covering on the cross beam is 90 essentially a protective one, and should occasion require, said beam may be detached from the angular sockets and in this manner present the opposite supporting side thereof, 95 or the beam may be removed as an entirety, and a new one substituted. Furthermore, said beam is reinforced by the braces 7 and permit the imposition of considerable weight thereon.

100 It should be understood that in its broader aspects the invention comprehends not only the employment of the various means described, but of equivalent means for performing the recited functions.

105 While the arrangement shown is thought, at the present time, to be preferable, it is desired to reserve the right to effect such modi-

fications and variations thereof as may come fairly within the scope of the appended claims.

Having thus described the invention, what I claim, is:

1. A mechanic's trestle, comprising, in combination, a pair of uprights, a cross beam, metallic strips secured on opposite sides of said uprights and beam, the latter being detachably connected by right-angular metallic sockets, braces for said sockets, a pair of substantially triangular shaped metallic casings, legs secured to the exterior inclined sides of said casing, and a centrally disposed socket within said casing, said uprights being adapted to move therein, and screws carried by the casing for engaging the metallic coverings of the uprights and thereby securing the latter in their adjusted position.
  2. A mechanic's trestle, comprising, in combination, a pair of uprights, a cross beam, metallic strips secured on opposite sides of said uprights and beam, the latter being detachably connected by right-angular metallic sockets, the inner side of each socket lying contiguous the upper horizontal portions thereof and serving as a stop for said beam, braces for said sockets, a pair of substantially triangular shaped metallic casings, legs secured to the exterior inclined sides of said casing, and a centrally disposed socket within said casing, said uprights being adapted to move therein, and screws carried by the casing for engaging the metallic coverings of the uprights and thereby securing the latter in their adjusted position.
  3. A mechanic's trestle, comprising, in combination, a pair of uprights, a cross beam, metallic strips secured on opposite sides of said upright and beam, the latter being de-
- tachably connected by right angular metallic sockets, braces for said sockets, a pair of substantially triangular shaped metallic casings, legs secured to the exterior inclined side of said casing, the latter having spaces 45 on opposite sides of the centrally disposed socket, said spaces being closed at the top, and open at the bottom for permitting access to the fastening means of said legs, said uprights being adapted to move in said medially arranged socket, and screws carried by the casing for engaging the metallic covering of the uprights and thereby securing the latter in their adjusted positions.
4. A mechanic's trestle, comprising, in combination, a pair of uprights, a cross beam, metallic strips secured on opposite sides of said uprights and beam, the latter being detachably connected by right-angular metallic sockets, the inner side of each socket lying contiguous the upper horizontal portions 60 thereof and serving as a stop for said beam, braces for said sockets, a pair of substantially triangular shaped metallic casings, legs secured to the exterior inclined sides of said casing, the lower terminals of the horizontal portions of said right angular supports being adapted to engage the upper terminals of said casing, a centrally disposed socket within said casing, said uprights being 65 adapted to move therein, and screws carried by the casing for engaging the metallic coverings of the uprights and thereby securing the latter in their adjusted positions.

In testimony whereof I hereunto affix my signature in presence of two witnesses.

MARLIN CRONER.
